TELEPHONE RECEIVING APPARATUS

Filed Oct. 9, 1924

UNITED STATES PATENT OFFICE.

SIDNEY GEORGE BROWN, OF NORTH ACTON, ENGLAND.

TELEPHONE RECEIVING APPARATUS.

Application filed October 9, 1924, Serial No. 742,716, and in Great Britain November 30, 1923.

This invention relates to telephone receiving apparatus in general and more particularly for use in connection with wireless telegraphy or telephony.

5 The object of the present invention is to amplify weak electrical currents such as are derived for instance from a crystal detector to such an extent that they will operate a loud speaker; more particularly, the invention has for its object the provision of a 10 unitary mounting in which the microphone amplifier is insulated from the telephone receiver so that mechanical vibration produced by the latter cannot be transmitted 15 through the mounting to the amplifier to affect the operation of the microphone.

With such object, the invention consists in the improved apparatus for transmitting or reproducing sound as hereinafter described and more particularly pointed out in the claims.

In order that the said invention may be clearly understood and readily carried into effect, one form will now be described by 25 way of example with reference to the accompanying drawings, in which:—

Figure 1 is a vertical section of the complete instrument;

Figure 2 is a plan with the sound horn 30 and the cover or casing of the amplifier removed and showing the differential microphone in section, and

Figure 3 is a diagram of the connections.

A metal base, A, is provided which carries 35 both the amplifier and the telephone receiver, the latter being enclosed in a casing, a, which forms an integral part of the base, A, and is raised from the base on the legs, a'. The casing, a, has at its upper side a 40 central hollow boss, a², which receives the smaller end of the sound horn or trumpet, B, which is of any ordinary form. The casing a is open at its under side and the base plate A has a coincident opening immediately below to permit the insertion of 45 the mechanism of the telephone receiver into the casing a. The base, A, is rounded and of elongated form with a larger and smaller end in plan, as shown in Figure 2, the larger 50 end receiving the microphone amplifier and the smaller end carrying the telephone receiver casing. The larger end is of annular form, providing an opening of large diameter within the flanged rim, a³, to which is 55 secured the thick rubber mat or support, C.

This is secured around its edge to the underside of the flanged rim, a³, by means of the stiffening plates, e, and set screws, c', the plates firmly clamping the rubber support, 60 C, to the flanged rim, a³.

On the upper side of the support or mat, C, is firmly secured the stout bracket, D, which carries the microphone amplifier, the flange, d, of the bracket being clamped upon the support, C, by the set screw, d', and the clamping plate, c², placed below the support, C, the plate, c², giving the necessary 65 rigidity to the centre of the rubber support.

The amplifier magnet, E, is mounted on the upright face of the bracket, D, in an 70 adjustable manner by the bolts, F, F', the bolt, F, being screwed into the bracket, D, and clamped to the two legs of the magnet, which is of horseshoe form, towards the pole 75 end by the clamping plates, f, and nuts, f', while the bolt, F', which is placed towards the other end of the magnet, is provided with a spring, f², placed between the bracket, D, and one of the clamping plates, f³, so as to press the round end of the magnet 80 resiliently away from the bracket. The mounting of the bolt, F, is sufficiently yielding 85 to permit a small angular adjustment of the magnet according to the setting of the bolt, F', which is provided at its outer end with an adjusting screw, G, which allows a limited turning movement, the screw slightly lengthening or shortening the effective 90 length of the bolt, F', so that the pole end of the magnet may be adjusted in position through a very small distance with great accuracy.

The pole end of the magnet carries the pole pieces, f⁴, which are mounted upon a 95 chanfered portion on the ends of the magnet so as to project at an angle of about 45°, these pole pieces carrying the receiving coils, H, and terminating in pole members, f⁵, placed closely adjacent to the stiff steel reed, J, which is rigidly mounted at j, towards 100 one end on the face of the bracket, D. The reduced end, j', of the reed is rigidly connected through the rod, k, to the central plate or electrode, k', of the differential microphone, K, which is of known type, the plate, k', lying between two layers of carbon granules in the cell, k², of the microphone 105 casing, the granules filling the spaces between the central plate and the end plates, k³, k⁴, which are usually of carbon. The 110

plates are, of course, insulated from one another excepting through the carbon granules.

The telephone receiver, L, is of the well known "Brown loud speaker" type, comprising a light conical diaphragm, l, mounted on the end of the steel reed, l', which is vibrated by the receiving electromagnet, l², the poles of which are close to the reed. The usual adjustments are provided and as the device is a known one there is no need to describe it in detail. The centre of the conical diaphragm lies immediately below the hollow boss, a, receiving the end of the sound horn, B, so that the sound vibrations emitted by the diaphragm, l, pass through the expanding horn.

The only material distinction between the telephone receiver, L, as employed in this device and as hitherto used lies in the windings, M, of the electromagnet, l², and the circuits are shown in Figure 3 where the windings, M, of the receiver magnet are shown as two pairs of coils which are wound differentially. For convenience the base, A, is employed as part of the circuit and the coils, M, are connected to the base in the manner indicated, the connection being carried from opposite ends of the two pairs of coils, while the other ends are connected, respectively, to the two outer plates, k³ and k⁴, of the microphone. The positive terminal, N, of the source of current supplied to the microphone is also connected to the frame, A, while the negative pole, N', is connected to the centre plate, k', of the microphone. The reed, J, of the relay is indicated as attached to the plate, k', and the coils, H, of the electromagnet E, are connected to the terminals, h, to which are attached the connections from the source of weak electrical currents to be magnified, such as those furnished by a crystal detector used in wireless telegraphy or telephony.

It will be seen that any oscillation of the reed, J, due to the weak currents passing through the amplifier receiving coils, H, causes the centre plate, k', of the microphone to vibrate and vary the current in opposite directions between the centre plate and the two outer plates, k³ and k⁴, with the result that the greatly magnified currents in the microphone circuit cause correspondingly increased effects on the reed, l', of the telephone receiver, L.

The source of current connected to the terminals, N, N', may be in the form of a battery of about 6 volts, a very small current being required as the resistance of the microphone and the telephone windings is considerable. The amplifier is, therefore, suitable for use with dry cells as the source of the microphone current.

The complete microphone amplifier is enclosed in the detachable cover or case, O,

mounted upon the rim, a³, of the base, A, and secured by bayonet joint or other simple connections. On the top of this case and independent of any connection with the amplifier is the magnetic adjuster, P, in the form of a knob mounted to turn freely around the stem, p, which is secured in the top of the case and carrying the small permanent magnet, p', which consists of a simple straight rod highly magnetized and passing transversely through the knob, P, at a short distance from the axis. The magnet, p', is situated over the amplifier magnet, E, and on turning the knob it can take up any angular position relatively to the magnet, E. It is found that the amplification obtainable can be greatly increased by suitably adjusting the knob, P, the effect of the magnetic field due to the small magnet, p', greatly influencing the action of the amplifier magnet on the reed, J. The knob is, therefore, turned by the listener during the reception of sound until the sound is at a maximum, or if it is too loud the magnetic adjuster can be turned to reduce it to any required degree.

Having now described my invention, what I claim as new and desire to secure by Letters Patent is:—

1. A mounting for loud speaker apparatus comprising a base plate having an opening in one end thereof, a telephone receiver mounted on the other end of said plate, a sound insulating mat secured to the base plate within said opening, a cover seated on the base plate over the sound insulating mat to provide a closed chamber, and a microphone amplifier mounted in said chamber on the mat and having electrical connections with the telephone receiver and also electrical connections leading to the exterior of the chamber to contact terminals for the circuit of the weak current that is to be amplified.

2. A mounting for loud speaker apparatus comprising a base plate having an opening in one end thereof, a casing on the other end closed at its top except for a sound outlet, a telephone receiver mounted in said casing, a sound insulating mat clamped to the base plate within said opening, a cover removably seated on the base plate over the insulating mat to form a closed chamber, a bracket within said chamber secured on said mat, and a microphone amplifier mounted on the bracket within the chamber and having electrical connections with the telephone receiver and also connections leading to the exterior of the chamber to contact terminals for the circuit of the weak current that is to be amplified.

3. A mounting for loud speaker apparatus comprising a base plate having openings in its opposite ends, a cylindrical casing on one end of the base plate over the opening therein and having an open bottom opposite to the opening in the adjacent end of the base

plate, said casing being provided with a closed top having a hollow boss projecting therefrom to provide a sound outlet, a telephone receiver in said casing, said base plate having a flanged rim at the opening in its other end, a sound insulating mat removably attached in the inner side of the flanged rim, a cover detachably seated on the base plate around said rim and over said mat to provide a closed chamber, a bracket removably clamped on the mat, and a microphone amplifier carried by said bracket within said chamber and having electrical connections leading to the exterior of the chamber to contact terminals for the circuit of the weak current that is to be amplified, said amplifier also having electrical connections with the telephone receiver.

In testimony whereof I have signed my name to this specification.

SIDNEY GEORGE BROWN.
